(57) **CLAIM**

The ornamental design for a pathogen containment device, as shown and described.

DESCRIPTION

FIG. 1 is a top-left front view of the pathogen containment device.

FIG. 2 is a bottom-right rear view of the pathogen containment device.

FIG. 3 is a front view of the pathogen containment device.

FIG. 4 is a rear view of the pathogen containment device.

FIG. 5 is a left side view of the pathogen containment device.

FIG. 6 is a right side view of the pathogen containment device.

FIG. 7 is a top view of the pathogen containment device.

FIG. 8 is a bottom view of the pathogen containment device.

FIG. 9 is a top-left front view a first alternative embodiment of the pathogen containment device.

FIG. 10 is a bottom-right rear view of the pathogen containment device of FIG. 9.

FIG. 11 is a front view of the pathogen containment device of FIG. 9.

FIG. 12 is a rear view of the pathogen containment device of FIG. 9.

FIG. 13 is a left side view of the pathogen containment device of FIG. 9.

FIG. 14 is a right side view of the pathogen containment device of FIG. 9.

FIG. 15 is a top view of the pathogen containment device of FIG. 9.

FIG. 16 is a bottom view of the pathogen containment device of FIG. 9.

FIG. 17 is a top-left front view a second alternative embodiment of the pathogen containment device.

FIG. 18 is a bottom-right rear view of the pathogen containment device of FIG. 17.

FIG. 19 is a front view of the pathogen containment device of FIG. 17.

FIG. 20 is a rear view of the pathogen containment device of FIG. 17.

(Continued)

FIG. 21 is a left side view of the pathogen containment device of FIG. 17.

FIG. 22 is a right side view of the pathogen containment device of FIG. 17.

FIG. 23 is a top view of the pathogen containment device of FIG. 17.

FIG. 24 is a bottom view of the pathogen containment device of FIG. 17.

FIG. 25 is a top-left front view a third alternative embodiment of the pathogen containment device.

FIG. 26 is a bottom-right rear view of the pathogen containment device of FIG. 25.

FIG. 27 is a front view of the pathogen containment device of FIG. 25.

FIG. 28 is a rear view of the pathogen containment device of FIG. 25.

FIG. 29 is a left side view of the pathogen containment device of FIG. 25.

FIG. 30 is a right side view of the pathogen containment device of FIG. 25.

FIG. 31 is a top view of the pathogen containment device of FIG. 25; and,

FIG. 32 is a bottom view of the pathogen containment device of FIG. 25.

The dash-dash broken lines depict portions of the pathogen containment device that form no part of the claimed design.
